Patented Oct. 24, 1967

209,005

FLOODLIGHT

Buell Moore, Houston, Tex., assignor to Esquire, Inc.,
Houston, Tex., a corporation of Delaware

Filed May 6, 1966, Ser. No. 2,206

Term of patent 14 years

(Cl. D48—20)

FIG. 1 is a perspective view as seen from the front, top and one side of a floodlight embodying my design;

FIG. 2 is a perspective view as seen from the back, bottom and other side of the floodlight mounted on a bracket secured to the bottom thereof;

FIG. 3 is a perspective view as seen from the front, bottom and other side of the floodlight; and

FIG. 4 is an elevational view as seen from the bottom of the floodlight mounted on a bracket secured to the other side thereof.

I claim:

The ornamental design for a floodlight, substantially as shown and described.
